INDUSTRIAL TRUCK

Roy C. Howell, Lakewood, Ohio

Application November 22, 1938, Serial No. 241,806

8 Claims. (Cl. 214—113)

This invention relates to industrial trucks of the type used for hoisting and transporting loads on a lift platform mounted for vertical movement at the forward end of the truck frame.

5 To provide a high lift, industrial trucks have been provided with telescopic standards which are extended as the platform is lifted. Such high lift trucks are, however, unsuitable for use in piling material in or removing material from 10 boxcars or low ceilinged rooms of warehouses, because they require a clearance equal to the full height of the extended standards.

The present invention has for its object to provide a combination low lift and high lift truck 15 having a telescopic standard which may be extended for high lifts, but which provided with a hoisting mechanism for the lift carriage by which the carriage may be lifted to the top of the standard whether the standard be extended or collapsed.

20 A further object is to provide a truck in which the lift carriage is operated by the movable section of the standard for high lifts and in which the lift carriage may be elevated to the top of the collapsed standard by the hoisting means.

25 A further object is to provide a simple and efficient means for tilting the lift platform and elevating the same in tilted position.

With the above and other objects in view the 30 invention may be said to comprise the truck as illustrated in the accompanying drawings herein-after described and particularly set forth in the appended claims together with such variations and modifications thereof as will be apparent 35 to one skilled in the art to which the invention appertains.

Reference should be had to the accompanying drawings forming a part of this specification, in which:

40 Figure 1 is a side elevation of a truck embodying the invention;

Fig. 2 is a fragmentary front elevation of the lower end of the guide standard upon which the lift platform is slidably mounted, viewed as indicated at 2—2 in Fig. 1;

Fig. 3 is a fragmentary side elevation of the forward end of the truck showing the lift platform in tilted position in full lines and in load pick-up position in dotted lines;

50 Fig. 4 is a diagrammatic view of the fluid pressure hoisting and tilting cylinders together with the fluid pressure supplying and controlling means;

55 Fig. 5 is a front elevation of the truck with por-

tions of the lift carriage and the guide standard broken away and shown in section;

Fig. 6 is a vertical section indicated at line 6—6 of Fig. 5;

Fig. 7 is a detail sectional view on an enlarged 5 scale showing the latch which controls the extension of the guide standard;

Fig. 8 is a side elevation of the latch controlling lever;

Fig. 9 is a top plan view of the guide standard 10 hoisting mechanism;

Fig. 10 is a diagrammatic view showing the lift platform in its uppermost position with the guide standard unextended;

Fig. 11 is a diagrammatic view showing the lift 15 platform in its uppermost position with the guide standard extended; and

Fig. 12 is a diagrammatic view of the lift platform in load-carrying position on a standard provided with cams for tilting the load lifting carriage as it is elevated.

In the accompanying drawings the invention is 20 shown applied to an industrial truck having a frame 1, a front axle 2 upon which traction wheels 3 are mounted, and rear steering wheels 4 mounted on forks 5 which have vertical spindles 6 journaled in the frame. A laterally facing driver's seat 7 is provided on the frame and the usual steering column 8 and brake and clutch pedals 9 and 10 are provided in front of the driver's seat.

The truck is propelled by means of an engine mounted in a suitable housing 11, the traction wheels 3 being driven through suitable driving connections in the housings 12. At the forward end thereof the frame 1 is provided with side plates 13 which are rigidly attached to the frame and extend forwardly between the wheels 3. Between the side plates 13 there is mounted a guide standard indicated generally by the numeral 14 which is supported on the axle 2. A load lifting carriage 15 is mounted for vertical travel on the standard 14, the carriage 15 being provided with a forwardly projecting load-carrying platform 16.

The standard 14 is an extensible standard consisting of a lower section attached to the truck frame and a movable section telescopically connected to the lower section. The lower section of the standard consists of a pair of inwardly facing channels 17 and the movable section consists of two outwardly facing channels 18, the flanges of which receive the flanges of the channel posts 17 between them as best shown in Fig. 9. Suitable keys 19 are provided between the flanges of the channels 17 and 18 to guide the channels 18 in 45 50 55

40 45 50 55

Fig. 5 is a front elevation of the truck with por-

their vertical movement on the channel posts 17. The channel posts 17 are attached at their lower ends to a bearing member 20 through which the axle 2 extends. The upper ends of the channel bars 17 are connected by a channel cross bar 17A and the lower ends of the channels 18 by a cross bar 21.

For hoisting the carriage 15 and for extending the standards 14, a hydraulic cylinder 22 is mounted between the channel posts 17. The cylinder 22 is attached at its lower end to the bearing member 20 and has a vertically movable piston 23 which carries a sprocket 24 at its upper end. A sprocket chain 25 is connected by an anchor bolt 26 to the bearing member 20 and extends up over the sprocket 24 and downwardly in front of the cylinder. The depending portion of the chain 25 carries a lifting member 27 which is in the form of a hook to engage with a cross shaft 28 on the carriage 15.

The carriage 15 has a pair of rearwardly extending arms 29 which extend rearwardly between the telescopically connected channel bar of the standard. The arms 29 of the carriage are connected by the cross shaft 28 adjacent the lower edges of the arms and forwardly of the standards 14. Above the shaft 28 the arms are connected by a cross rod 30 and rearwardly of the standards 14 they are connected adjacent their upper edges by a cross shaft 31. The shafts 28 and 31 project through the arms 29 and carry rollers 32 and 33 which bear against the front and rear sides of the channel bars 18. The lifting member 27 has a flange 34 which, in the lowermost position of the lifting member, rests upon the top of the cross bar 21 which connects the lower ends of the channel members 18 and the lifting member is adapted to be connected to the cross bar 21 to lift the channels 18 and extend the standard by means of a latch 35 which is normally held in a position projecting beyond the rear face of the lifting member 27 so as to engage with the lower edge of the cross bar 21 when the lifting member is raised.

The outer end of the latch member 35 is beveled at 36 on the under side so that the latch member will be retracted by engagement with the cross bar 21 as the carriage 15 is lowered. The latch member 35 is normally pressed rearwardly by means of a spring 37 so that the latch member will normally snap to a position beneath the cross bar 21 when the carriage 15 reaches its lowermost position. The latch 35 normally connects the cross bar 21 to the lift member 27 so that when the piston 23 is elevated the movable section of the standard is raised with the carriage 15. It is desirable, however, to extend the standard only for high lifts, and suitable means is provided for rendering the latch 35 inoperative to lift the movable section of the standard. The latch controlling means herein shown is a plunger 38 which is slidably mounted in a casing 39 immediately at the rear of the cross bar 21. The plunger 38 is normally projected forwardly beneath the cross bar 21 by means of a spring 40 in the casing 39. The spring 40 is stronger than the spring 37 of the latch so that when the lifting member 27 is in its lowermost position the latch 35 may be held by the plunger 38 in a position clear of the cross bar 21. When the plunger 38 is projected into engagement with the latch 35, the latch 35 rides from the face of the plunger 38 onto the front face of the cross bar 21 to permit the lifting member 27 to move past the cross bar 21, and on the return of the member 27 to

its lowermost position the latch rides down the outer face of the cross bar 21 and onto the end face of the plunger 38.

Means is provided for retracting the plunger 38 in opposition to the spring 40 and for holding the plunger in retracted position to permit the latch 35 to engage the cross bar 21 for causing the standard 14 to be extended. The plunger is retracted by means of a flexible cable 41 attached to the plunger 38 and extending to a lever 42 mounted on the frame 11. The lever 42 is provided with a pawl 43 which engages with a sector plate 44 to retain the lever 42 in the position in which the plunger 38 is retracted. Whenever the pawl 43 is tripped the spring 40 returns the plunger 38 to latch-releasing position.

Each of the channels 18 of the movable section of the standard has a sprocket 45 at its upper end, and over each of the sprockets 45 there runs a chain 46. Each chain is attached at one end to an arm 29 of the lift carriage 15. The opposite end of each chain 46 depends from its sprocket 45 and has a counterweight 47 attached thereto. The length of the chains 46 is such that when the carriage 15 is lifted without extending the standard 14, the counterweights 47 are adjacent the lower end of the standard when the carriage 15 is adjacent the upper end of the standard. When the hoist cylinder 22 is operated with the lift member 27 disconnected from the movable section of the standard, counterweights 47 move from a position adjacent the top of posts 17 to a position adjacent the lower end thereof as the carriage is elevated from lowermost position to a position adjacent the upper end of the posts 17. When the cross bar 21 is connected by the latch 35 to the lifting member 27, the movable section of the standard is lifted with the carriage 15. As the carriage is lifted by the lift member 27 the sprockets 45 are elevated and the counterweights 47 engage with stop members 48 attached to posts 17 adjacent their upper ends. Each stop member 48 is in the form of an angle bracket having apertures 49 through which a chain 46 extends. With the counterweights in engagement with the stop members 48, upward movement of the hoisting piston 23 will draw the chains 46 over the sprockets 45 and lift the carriage 15 off the hook shaped lifting member 27, causing the carriage to move upwardly past the upper ends of the posts 17 and along the channels 18. The length of the chains 46 is such that when the movable section of the standard is moved to its uppermost position the carriage 15 is lifted to adjacent the upper end of the movable section as shown in Fig. 11.

It is desirable that the load carrying platform be tilted rearwardly to insure retention of the load during travel of the truck and during the elevating operation. Tilting of the carriage may be accomplished by pivotally mounting the standard 14 upon the axle 2.

As best shown in Fig. 6, the bearing member 20 is mounted to rock on the axle 2 and provided with a rearwardly extending arm 52 which is connected to the piston 53 of a fluid pressure cylinder 54. The pivotal movement of the standard 14 is limited by means of pins 50 attached to the channel posts 17 and extending through short arcuate slots 51 in the side plates 13.

As best shown in Fig. 4, of the drawings, liquid under pressure is applied to the cylinders 22 and 54 by means of a pump 55 which may be driven from the engine of the truck, the liquid passing through inlet pipe 56 and an outlet pipe 57, the 75

inlet and outlet pipes extending to a liquid reservoir 58, the outlet pipe 57 having a pressure limiting relief valve 57a adjacent the reservoir. A pipe 59 leading from the pump outlet pipe 57, extends to a valve casing 60 in which there is mounted a sliding spool valve 61 operated by lever 62. The valve 61 has spaced plungers 63, 64 and 65 providing chambers in the valve casing through which communication may be established between the pipe 59 or a return pipe 66 to the reservoir 58 with a pipe 67 leading to the cylinder 54. A second pipe 68 leading from the pump outlet pipe 57 extends to a valve casing 69 which has a spool valve 70 operated by a lever 71. The valve 70 has spaced plungers 72, 73 and 74 which provide chambers in the valve casing for establishing communication between the pipe 68 or a return pipe 75 with a pipe 76 leading to the fluid pressure cylinder 22.

20 In the operation of the truck, as shown in Fig. 3, the platform 16 may be positioned in a horizontal position or in a slightly forwardly inclined position for loading and, after loading, may be tilted by means of the fluid pressure cylinder 25 rearwardly, to a position such that there is no danger of the load falling off the platform.

A modified form of tilting device is shown in Fig. 12 in which the channels 18 are provided on the front and rear sides thereof with cam strips 77 and 78 which terminate a short distance above the lower end of the post. The lower ends of these strips are beveled as shown at 79 and 80, the beveled end 79 being somewhat below the beveled end 80, so that during the initial lifting movement of the carriage 15 the rollers 32 and 33 ride up the inclines 79 and 80 to force the rollers farther apart to tilt the carriage to the position shown in full lines of Fig. 12.

Furthermore, it is understood that the particular form of apparatus shown and described, and the particular procedure set forth, are presented for purposes of explanation and illustration and that various modification of said apparatus and procedure can be made without departing from my invention as defined in the appended claims.

What I claim is:

1. An industrial truck comprising a frame, an extensible guide standard comprising telescopically connected sections carried by the frame at the forward end thereof, one of said sections being attached to the truck and another being movable on the attached section, a load lifting carriage mounted for vertical movement on the standard, hoisting means, means for connecting said hoisting means to said carriage only to lift the same to the upper end of the unextended standard while said movable standard section remains stationary, means for connecting said hoisting means both to said carriage and to the movable section of the standard to simultaneously lift the movable section of the standard and carriage, and an auxiliary hoisting means operated by said movable section for lifting the carriage along the movable section during upward travel of the movable section.

2. An industrial truck comprising a frame, an extensible guide standard comprising telescopically connected sections carried by the frame at the forward end thereof, a load lifting carriage mounted for vertical movement on the standard, hoisting means, means for connecting said hoisting means to said carriage to lift the same to the upper end of the unextended standard, means

operable when said carriage is in a lowered position for connecting a movable section of the standard to said hoisting means to extend the standard, and means operated by a movable section of the standard for moving the carriage upwardly along the movable section as the movable section is moved upwardly.

3. An industrial truck comprising a frame, a guide standard mounted on said frame, said standard comprising a lower section attached to said frame and a movable section telescopically connected to said lower section and movable from a position in which its lower end is adjacent the bottom of the lower section to a position in which its lower end is adjacent the top of the lower section, a load lifting carriage mounted for vertical movement on the standard, a lifting member engageable with said carriage and mounted on the lower standard section for movement from a position adjacent the lower end thereof to a position adjacent the top thereof, means for actuating said lifting member releasable means for connecting said movable standard section to said lifting member, and means operated by said movable standard section for lifting said carriage out of engagement with said lifting member and moving the same upwardly past the lower section and along the movable section.

4. An industrial truck comprising a frame, a guide standard mounted on said frame, said standard comprising a lower section attached to said frame and a movable section telescopically connected to said lower section and movable from a position in which its lower end is adjacent the bottom of the lower section to a position in which its lower end is adjacent the top of the lower section, a load lifting carriage mounted for vertical movement on the standard, a lifting member engageable with said carriage and mounted on the lower standard section for movement from a position adjacent the lower end thereof to a position adjacent the top thereof, means for actuating said lifting member, releasable means for connecting said movable standard section to said lifting member, and an auxiliary carriage hoisting means comprising a guide member carried by said movable section, a flexible hoisting member running over said guide and attached at one end to said carriage, a counterweight attached to the opposite end of said hoisting member and a stop for limiting the upward movement of said counterweight.

5. An industrial truck having a frame, a standard mounted on said frame, said standard comprising a lower section attached to the frame and a movable section telescopically connected with the lower section, a load lifting carriage mounted for travel on said standard, means for hoisting said carriage comprising a cylinder carried by the lower section of the standard and having a vertically movable piston, a sprocket carried by said piston at its upper end, a chain attached to the lower section of the standard at one end extending over said sprocket and having a hook engageable with said carriage at its opposite end, a second sprocket at the upper end of said movable standard section, a chain attached at one end to said carriage and extending over said sprocket, a counterweight attached to the opposite end of said chain, a stop member carried by the lower section of the standard and engageable with said counterweight, and releasable means for connecting the lower end of the

movable standard section to said first mentioned chain.

6. An industrial truck comprising a frame, a front axle upon which traction wheels are mounted and rear steering wheels, a standard having its lower end pivotally mounted on said axle between said traction wheels, said standard comprising telescopically connected sections, a load lifting carriage mounted for vertical movement on said standard, fluid pressure operated means mounted on the standard for extending said standard and lifting said carriage along the standard, fluid pressure means for swinging said standard rearwardly on its pivot to tilt said carriage, and stop members on the standard for limiting the swinging movements of the standard.

7. An industrial truck comprising a frame, a standard attached to the forward end of said frame, said standard comprising a section attached to the frame and a movable section exteriorly engaging said fixed section, a load lifting carriage having vertically offset rollers engaging the front and rear sides of said movable section, hoisting means, means for connecting said hoisting means to said movable standard section,

means connecting said carriage to said movable standard section for movement in unison with the movable section, and auxiliary hoisting means carried by said movable section and operable after movable section has been lifted to a predetermined height to lift said carriage at a speed greater than that of the movable section, thereby causing the carriage to travel upwardly upon the vertically moving standard section.

8. An industrial truck comprising a frame, a standard attached to the forward end of said frame, said standard comprising a section attached to the frame and a movable section exteriorly engaging said fixed section, a load lifting carriage having vertically offset rollers engaging the front and rear sides of said movable section, hoisting means, means for connecting said hoisting means to said carriage and to said movable standard section, auxiliary hoisting means carried by said movable section and operable upon a predetermined movement of said section to lift said carriage at an increased speed, and cams carried by said movable section in the path of said rollers for tilting said carriage.

ROY C. HOWELL.
